United States Patent

Des. 234,846

Patented Apr. 15, 1975

234,846

AIR COCK

Donald A. Gallant, Charlotte, N.C., assignor to
Pneumapulse Company, Charlotte, N.C.

Filed Aug. 24, 1972, Ser. No. 283,568

Term of patent 14 years

Int. Cl. D23—01

U.S. Cl. D23—19

FIG. 1 is a perspective view of an air cock showing my new design;

FIG. 2 is a top plan view thereof;

FIG. 3 is a side elevational view thereof, the opposite side being a mirror image of the side shown;

FIG. 4 is an end elevational view thereof, showing the operating lever in its closed position; and

FIG. 5 is a bottom plan view thereof.

I claim:

The ornamental design for an air cock, as shown and described.
